United States Patent Office

Des. 175,981
Patented Nov. 1, 1955

175,981

MONEY CLIP OR SIMILAR ARTICLE

Sidney Rubeck, New York, N. Y.

Application April 4, 1955, Serial No. 35,349

Term of patent 14 years

(Cl. D17—3)

Fig. 1

Fig. 3

Fig. 2

Fig. 4

Fig. 5

Fig. 1 is a plan view of a money clip or similar article showing my new design.

Fig. 2 is an edge view thereof.

Fig. 3 is a perspective view of the money clip illustrating the opposite side of Fig. 1.

Fig. 4 is a rear elevational view of the money clip.

Fig. 5 is a front perspective view illustrating the money clip partially in open position.

The dominant feature of my design resides in the portions shown in solid lines.

I claim:

The ornamental design for a money clip or similar article, substantially as shown and described.
